FREE PUMP CONTROL SYSTEM

Charles L. English, 2294 E. 25th Place, and John B. Woods, P.O. Box 7526, both of Tulsa, Okla.

Filed Nov. 5, 1962, Ser. No. 235,308
11 Claims. (Cl. 103—46)

This invention relates generally to improvements in valves, and more particularly, but not by way of limitation, to an improved control system for a subsurface hydraulic pump installation.

As it is well known in the production division of the oil industry, subsurface hydraulic pumps are being used more and more for removing oil from wells which have ceased to produce by natural gas pressure. There are basically two types of subsurface hydraulic pump installations. In one type of installation, known as the insert type, the subsurface hydraulic pump is secured on the lower end of a tubing which requires the complete removal of either one or two strings of tubing when the subsurface pump requires replacement or repair.

The second and perhaps most popular subsurface pump installation is what is known as the free pump type. In this type of system, one relatively large string of tubing and one smaller string of tubing are installed in the well and interconnected at their lower ends. The subsurface hydraulic pump is of a size to move through the larger string of tubing in the nature of a piston when high pressure fluid is imposed on the upper end of the large string. The pump is in operating position when seated at the lower end of the large string of tubing. The pump is removed from the well by imposing high pressure fluid on the small string of tubing which forces the subsurface pump upwardly through the large string, again in the nature of a piston. When seated at the lower end of the large string of tubing, the pump may be operated by high pressure power fluid being forced downwardly through either the large string or the small string, depending upon whether the pump is latched into position when seated at the lower end of the large string. In either event, the exhausting power fluid and a volume of well fluid are pumped upwardly through the other tubing to the surface for storage and treatment. It will thus be seen that a valving or control system must be provided at the well head for feeding high pressure power fluid into either the large string or the small string, and for directing fluid from either of the tubing strings to storage facilities. The required control system must therefore provide what may be considered a four-way valving action.

Prior to the present invention, there have been two basic types of control systems used in industry. One type of control system uses a four-way, tapered plug-type valve which is unduly sensitive to pressure variations in the high pressure power fluid and is difficult to seal against the extremely high pressures of the power fluid. The second type of control system utilizes a pair of three-way valves requiring the use of four valve seats which are, of course, subject to wear and require frequent repair, since the valves are handling abrasive fluids.

The present invention contemplates a novel control system wherein the valve structure which is subject to abrasive fluids requires only two valve seats. In a preferred embodiment, the valve structure utilizes two ball-type valves and ball valve seats which are the most economical and durable type of construction for abrasive fluid service. In addition to the valve structure referred to, the present control system requires either a pair of hand-operated one-way valves, or a single three-way valve, but these valves are subjected only to clean power oil and will have long and trouble-free service lives. The flow of fluid to and from the large and smaller strings

2

of tubing is accomplished simply by closing one hand-operated valve and opening another hand-operated valve.

The present invention also contemplates a control system wherein the pressure of the power fluid being fed to either the large string or the small string of tubing will be automatically indicated, such that the operator of the system will be constantly advised of the condition of the system. The pressure indication is obtained by a valve assembly having one end connected to the large string of tubing and the other end connected to the small string of tubing. A simple ball valve moves between a pair of spaced valve seats when the pressure at the opposite ends of the valve assembly varies, whereby the higher pressure is admitted to the central portion of the valve assembly. The central portion of the valve assembly is connected to a pressure gauge in view of the operator of the system.

An object of this invention is to provide a control system for a free pump installation wherein the valve structure exposed to abrasive fluids utilizes the minimum number of valve seats.

Another object of this invention is to provide such a control system wherein the valve structure exposed to the abrasive fluids utilizes the most durable and economical valve seat and valve member constructions.

Another object of this invention is to provide a control system for the large and smaller strings of tubing of a free pump installation wherein the flow of fluid to and from the large and small strings of tubing may be controlled by simply operating a single three-way valve, for by closing one manual valve and opening another manual valve.

A further object of this invention is to provide a free pump control system wherein the fluid discharged from the larger string of tubing of the installation during removal of the subsurface pump will be directed into storage facilities or the like and will not be turned loose at the well head.

Another object of this invention is to provide a free pump control system wherein the highest pressure being imposed on either the large string or the small string of tubing of the pump installation will be automatically indicated for the operator of the system.

A still further object of this invention is to provide a free pump control system utilizing the maximum of conventional parts; which may be economically manufactured; which may be easily repaired and which may be easily operated by unskilled workmen.

Other objects and advantages of the invention will be evident from the following detailed description when read in conjunction with the accompanying drawings which illustrate our invention.

In the drawings:

FIGURE 1 is an elevational view of a subsurface hydraulic pump installation utilizing our novel control system, with portion of the pump installation being shown in section.

FIGURE 2 is an elevational view of a portion of the control system as viewed at the side opposite that shown in FIG. 1.

FIGURE 2A is an enlarged sectional view showing the connection of the small tubing to the valve body.

FIGURE 3 is a top view of a portion of the control system shown in FIGS. 1 and 2.

FIGURE 4 is a side elevational view of the valve body of the control system with the various couplings removed and with a portion of the passageways in the body being shown in dashed lines.

FIGURE 5 is a cross sectional view taken along lines 5—5 of FIG. 4 illustrating the details of construction of the pressure-measuring valve assembly.

FIGURE 6 is a sectional view taken along lines 6—6

of FIG. 4 illustrating the details of construction of the pressure-measuring valve assembly.

Referring to the drawings in detail, and particularly FIG. 1, reference character 10 generally designates the control system of this invention connected to the upper ends of a large string of tubing 12 and a smaller string of tubing 14. The tubing strings 12 and 14 extend in parallel relation through a wellbore (not shown) and are interconnected at their lower ends 16 and 18 in any suitable manner to provide communication between the tubing strings. A seating shoe 20 is normally positioned in the extreme lower end of the large string of tubing 12 and communicates with the wellbore through a well fluid inlet 22 formed in the extreme lower end of the large tubing string. A suitable subsurface hydraulic pump 24 of the "free" type is seated in the shoe 20 and extends upwardly in the large tubing string 12 in its normal pumping position. The pump 24 may be of the type to receive power oil through the smaller tubing 14 and exhaust a combination of exhausted power fluid and well fluid upwardly through the large tubing 12 if desired. However, for simplicity of illustration and explanation, it will be assumed that the pump 24 is of a type to receive power oil at its upper end from the large tubing 12 and to pump the exhausted power fluid and well fluid upwardly through the smaller tubing 14. It will be noted that downwardly facing cups 26 are provided on the upper end of the pump 24 for use in pumping the pump 24 upwardly through the large tubing 12, as will be described in detail below. Also, intermediate seals 28 are normally provided along the central portion of the pump 24 to separate the power oil and exhausting fluids flowing to and from the pump 24 in the conventional manner.

The control system 10 comprises a valve body 30 (the details of which will be described below) having two inlet lines 32 and 34 suitably secured to the opposite sides of the valve body 30 by couplings 36. The inlet lines 32 and 34 extend in parallel from a common power fluid supply line 38 suitably connected (not shown) to a source of high pressure power fluid. The power fluid is normally clean oil. The flow of the high pressure power fluid from the supply line 38 to the inlet lines 32 and 34 is controlled by a manually operated one-way valve 40 interposed in the inlet line 32 and a manually operated one-way valve 42 interposed in the inlet line 34. The valves 40 and 42 will be of conventional construction. It will also be understood that the two valves 40 and 42 may be replaced by a single three-way valve at the connection of the line 38 to the lines 32 and 34 if desired.

An outlet line 44 extends from the front of the valve body 30 to direct the fluid flowing from either the large tubing 12 or the smaller tubing 14 to suitable storage facilities (not shown). Another hand-operated valve 46 is preferably interposed in the outlet line 44 in the event it is desired to completely close in the installation. The valve 46 will be open during all normal operations of the control system 10. It is also desirable to provide a bypass line 48 connecting the power fluid line 38 to the outlet line 44 downstream of the valve 46 in the event it is desired to circulate power oil from the power oil source to storage facilities. A manually operated valve 50 is interposed in the bypass line 48 and is closed during all normal operations of the control system 10.

The control system 10 also includes a pressure gauge 52 mounted on the top of the valve body 30 and connected to register the highest pressure existing in either the large tubing 12 or the small tubing 14, as will be described in the detailed description of the valve body 30. Also, a suitable pump catcher 54 is mounted on the top of the valve body 30 in communication with the large tubing string 12 to receive and hold the pump 24

when the pump 24 is removed for repair or replacement, as will be described below.

The details of construction of the valve body 30 are illustrated in FIGS. 4 through 6. As shown in FIG. 5, 5 a bore or passage 56 is formed all the way through the valve body 30 from one side 58 to the opposite side 60 and communicates at its opposite ends with the inlet lines 32 and 34. An outlet port or bore 62 extends from the back 64 of the valve body 30 and intersects the central portion 66 of the passage 56. A large bore 68 is formed vertically all the way through the valve body 30 forwardly of the passage 56 for connection at its lower end with the large tubing string 12 and for connection at its upper end with the pump catcher 54 previously described in connection with FIG. 1. The large bore 68 communicates with one end portion 70 of the passage 56 by a cut-away portion 72 formed in the valve body 30 at the level of the passage 56. It may also be noted that the cut-away portion 72 is positioned above the upper end of the large tubing string 12 and below the lower end of the pump catcher 54 to provide constant communication between the bore 68 and the end portion 70 of the passage 56. Another vertical bore 74 is formed from the bottom of the valve body 30 forwardly of the passage 56 and extends upwardly in the valve body 30 to the level of the passage 56. The bore 74 is provided to connect with the smaller tubing string 14. Another horizontal bore 76 extends from the front 78 of the valve body 30 to the end portion 80 of the passage 56 and intersects the upper end portion of the bore 74 to provide constant communication between the smaller tubing string 14 and the end portion 80 of the passage 56. The extreme forward end of the horizontal bore 76 is provided with a bleed valve 82 (FIG. 3) for purposes to be described, but it may be noted that the bleed valve 82 is normally closed.

A novel shuttle valve 84 is positioned in the passage 56 to control the flow of fluid to and from the tubing strings 12 and 14 in response to different pressures applied at the inlet lines 32 and 34. The shuttle valve 84 comprises a 40 pair of ball valve seats 86 and 88 positioned on opposite sides of the central portion 66 of the passage 56, that is, on opposite sides of where the outlet port 62 intersects the passage 56. Each of the valve seats 86 and 88 is sealed in the passage 56 by a suitable O-ring 90 and is held against an outwardly facing shoulder 92 by a liner 94. Each liner 94 is reduced in diameter from its outer end to approximately the middle of the liner to assist in operation of the shuttle valve 84 as will be described. The outwardly facing shoulders 92 are formed either by a variation in the diameter of the passage 56 or by a separate spacer, and the liners 94 are retained in the passage 56 by the inlet lines 32 and 34, or by the couplings 36 used to connect the inlet lines 32 and 34 to the valve body. However, the liners 94 are preferably loosely fitted in the passage 56 to minimize the strength required. The liners 94 are held against the seats 86 and 88 by pressure on the shuttle valve, as will be described. It will also be noted that each liner 94 is provided with a plurality of circumferentially spaced slots 96 to provide substantially unrestricted flow of fluid from the passageway 56 to and from the tubing strings 12 and 14. The valve seats 86 and 88 are provided with outwardly facing seating areas 98 and 100 and are preferably provided with similar seating areas on the opposite sides thereof in order that the valve seats may be installed in either direction and may be reversed when the seating areas become worn.

A ball valve 102 is positioned in the passage 56 outwardly of the valve seat 86, and another ball valve 104 is positioned in the passage 56 outwardly of the valve seat 88 to cooperate with the seating areas 98 and 100, respectively. The ball valves 102 and 104 are sized to a sliding fit in the outer end portions of the respective liners 94 and are retained in spaced relation at a distance greater than the spacing between the valve seats 86 and 88 by a spacer member 106. The spacer 106 is preferably in the

form of a tube shaped at its opposite ends to contact the ball valves 102 and 104 without damaging the ball valves. The spacer 106 has an outer diameter of a size for a sliding fit of the spacer in the valve seats 86 and 88 so that the spacer will not interfere with the movements of the ball valves 102 and 104. It will also be noted that the spacer 106 has two sets of circumferentially spaced slots 108 in order that the spacer will not materially restrict the flow of fluid through the passageway 56 in any operating position of the spacer. Each set of slots 108 is of a length substantially corresponding to the spacing between the valve seats 86 and 88 to minimize the restriction of fluid flow in the passageway 56 and yet leave sufficient material in the spacer 106 for the strength required to unseat the ball valves 102 and 104.

The operation of the shuttle valve 104 may be determined from an examination of FIG. 5. When high pressure power fluid is being fed to valve body 30 through the inlet line 32, and is not being fed through the inlet line 34, the high pressure fluid in the end portion 70 of the passage 56 acts on the ball valve 104 to move the valves to the left and seat the ball valve 104 on the seating area 100 of the valve seat 88. In this position of the shuttle valve, the high pressure power fluid flows through the slots 96 in the right-hand liner 94 and through the cut-away portion 72 into the large vertical bore 68 for passage downwardly into the large tubing string 12. On the other hand, any fluid flowing upwardly through the smaller tubing string 14 at this time will flow upwardly through the smaller vertical bore 74, rearwardly through the horizontal bore 76 and then through the slots 96 in the left-hand liner 94 and the left-hand slots 108 in the spacer 106 into the end portion 80 of the passage 56. The fluid then has free passage through the central portion 66 of the passage 56, rearwardly through the right-hand slots 108 in the spacer 106 and then through the discharge port or outlet port 62 and outlet line 44.

When the pressure differential across the shuttle valve 84 is reversed, by imposing power fluid pressure in the inlet line 34 and cutting off power fluid pressure in the inlet line 32, the high pressure fluid acting on the ball valve 102 will move the ball valves to the right and seat the ball valve 102 on the seating area 98 of the valve seat 86. It will also be noted that each ball valve fits fairly closely in the respective liner 94 when the respective ball valve is in the outer end of the liner. Thus, when the ball valves are positioned as shown in FIG. 5, the pressure in inlet line 34 acts across the entire cross sectional area of ball valve 102; whereas, the pressure in inlet 32 acts on ball valve 104 only across the area of the seat 100. Thus, even though the pressures in the inlet lines 32 and 34 are equal, the shuttle valve 84 will start moving to the right. When the pressure in inlet 32 is decreased by a bleed-off to outlet line 44, the ball valve 102 will become seated on seat 86. It will then be apparent that the high pressure fluid may flow from the inlet line 34 through the end portion 80 of the passage 56 and through the bore 76 and the bore 74 downwardly into the through the smaller tubing string 14. On the other hand, any fluid flowing upwardly in the large tubing string 12 will be discharged through the bore 68, cut-away portion 72, end portion 70 of passage 56, central portion 66 of passage 56 and outwardly through outlet port 62 and outlet line 44. This reversal of fluid flow to and from the tubing strings 12 and 14 is obtained for insertion, operation and removal of the subsurface hydraulic pump 24 as will be described below. As also shown in FIG. 5, each of the inlet line couplings 36 may be provided with a counterbore 105 at its inner end to partially receive the ball valves 102 and 104 to reduce the required overall width of the valve body 30.

The structure utilized for registering the pressure in the tubing strings 12 and 14 by the pressure gauge 52 is illustrated in FIGS. 4 and 6. A horizontal bore 120 is formed from the side 58 of the valve body 30 (FIG. 6)

above and parallel with the passage 56 previously described in connection with FIG. 5. An outwardly facing shoulder 122 is formed in the medial portion of the bore 120 to receive and support a ball valve seat 124. A second ball valve seat 126 is retained in spaced relation in the bore 120 from the seat 124 by a perforated spacer 128 having an outer diameter smaller than the diameter of the respective portion of the bore 120. The seat 126 is in turn held by a plug 130 threadedly secured in the outer end of the bore 120. It will also be noted that the plug 130 is reduced in diameter near its inner end 132 and is provided with a partial bore 134 in its inner end which communicates with the bore 120 through radially extending ports or apertures 136. Both of the seats 124 and 126 are sealed in the bore 120 by suitable O-rings 138. A ball valve 140 is positioned in the spacer 128 and is of a size to roll freely in the spacer 128 into seating engagement with either of the seats 124 or 126 in response to pressure differentials in the seats 124 and 126, as will be described.

One vertical bore 142 is drilled from the top 144 of the valve body 30 downwardly in intersecting relation with the inner end portion 146 of the bore 120 and into communication with the end portion 70 of the passage 56. It will be noted here that this end portion 70 of the passage 56 is in constant communication with the large tubing string 12 as previously described in connection with FIG. 5. The upper end of the bore 142 is closed by a plug 147. Another vertical bore 148 is drilled from the top 144 of the valve body in intersecting relation with the bore 120 at the location of the inner end portion 132 of the plug 130 and extends downwardly into communication with the end portion 80 of the passage 56 previously described. The upper end of the bore 148 is closed by a plug 149. It will again be noted that the end portion 80 of the passage 56 is in constant communication with the smaller tubing string 14 as previously described in connection with FIG. 5. Thus, the pressure in the large tubing string 12 is constantly transmitted through the bore 142 and the right-hand valve seat 124 to act on the right-hand side of the ball valve 140; whereas, the pressure in the smaller tubing string 14 is constantly transmitted through the bore 148 and the valve seat 126 against the left-hand side of the ball valve 140. It will therefore be apparent that the ball valve 140 will be moved to the low pressure side and close off the valve seat 124 or 126 subjected to the lowest pressure. The higher pressure imposed on the ball valve 140 will be exerted through the ported spacer 128. This higher pressure is transmitted to the pressure gauge 52 through a horizontal bore 150 (see FIG. 4) drilled in the body 30 from the rear face 64 of the valve body, and then upwardly through a vertical bore 152 which intersects the bore 150. The pressure gauge 52 is threadedly secured in the upper end portion of the vertical bore 152. It will be understood that the outer end of the bore 150 is closed by a plug 153 to prevent leakage from the valve body 30.

Another important practical feature of the present control system is the connection of the small tubing string 14 to the valve head 30 as illustrated in FIG. 2A. As shown, an adapter 160 is threadedly secured in the lower end of the body 30 at the lower end of the vertical bore 74 described in connection with FIG. 5. A tubular mandrel 162 is slip-fitted in the lower end of the adapter 160 and is sealed therein by a suitable O-ring 164. The mandrel 162 is held in the desired position in the adapter 160 by a tapered locking ring or collar 166 threadedly secured around the lower end of the adapter 160. The tapered face 168 of the collar 166 cooperates with a correspondingly tapered portion 170 on the lower end of the adapter 160 to provide a wedging action when the collar 166 is threaded tight to provide a friction grip of the adapter 160 around the mandrel 162. The mandrel 162 has an offset 172 near its lower end to threadedly receive the upper end of the tubing string 14. It will thus be

apparent that the mandrel 162 may be turned in any desired direction to vary the spacing between the small tubing string 14 and the large tubing string 12 to accommodate substantially any existing subsurface pump installation.

Operation

Prior to installation of the pump 24 into operating position as illustrated in FIG. 1, let it be assumed that the normal valve in the seating shoe 20 is closed and the tubing strings 12 and 14 are full of oil, as will normally be the case. It will also be observed that the manual valves 40 and 42 will be closed when the pump 24 is removed. The pump 24 is inserted in the upper end of the large tubing strings 12 by removing the pump catcher 54 and simply dropping the pump into the large tubing; whereupon the tubing catcher 54 is replaced. The manual valve 40 is then opened to direct the high pressure power fluid through the inlet line 32. This high pressure fluid acts on the ball valves 104 and 102 to the positions shown in FIG. 5. As previously described, the high pressure power fluid then flows downwardly through the tubing string 12 and forces the pump 24 downwardly through the tubing string 12 until it becomes seated on the seating shoe 20 as illustrated in FIG. 1. During the downward movement of the pump 24, the fluid below the pump is forced upwardly through the smaller tubing string 14 where it enters the vertical bore 74 of the valve body 30. As previously described, this fluid then flows through the bore 76, the end portion 80 of the passage 56, the central portion 66 of the passage 56, and out through the outlet port 62 and outlet line 44 to the storage facilities.

When the pump 24 is seated as illustrated in FIG. 1, the high pressure power fluid is continually fed from the inlet line 32 downwardly through the tubing string 12 to operate the pump. The exhausting power fluid and pumped well fluid drawn in through the inlet 22 at the lower end of the installation are forced upwardly through the smaller tubing string 14 and discharged through the outlet line 44 to storage. While the high pressure power fluid is being directed through the large tubing string 12, the pressure of this fluid will be exerted through the valve seat 124 (FIG. 6) to move the small ball valve 140 to the left against the seat 126, such that this pressure will be applied on the pressure gauge 52 to advise the operator of the system of the highest pressure being imposed on the pump installation.

When it is desired to remove the pump 24 for replacement or repair, the manual valve 42 (FIG. 1) is opened and the valve 40 is closed. It will then be observed that the high pressure power fluid is fed through the inlet line 34 to react on the ball valve 102 of the shuttle valve assembly. The ball valves 102 and 104 are therefore moved to the right (with respect to FIG. 5) to seat the ball valve 102 on the valve seat 86. As previously described, the high pressure power fluid is then directed downwardly through the smaller tubing string 14, and the large tubing string 12 is opened to the outlet line 44. The high pressure power fluid flowing downwardly through the small tubing string 14 will first react on the intermediate seals 28 of the pump unit 24 and unseat the pump; whereupon this high pressure fluid flows upwardly through the large tubing string 12 and reacts on the downwardly facing cups 26 to move the pump 24 upwardly through the large tubing string 12. This operation is continued until the upper end of the pump 24 enters and is engaged by the pump catcher 54; whereupon the bypass valve 50 is opened to protect the power fluid source. The valve 42 and the valve 46 are closed. Also, to relieve any pressure existing in the tubing strings 12 and 14, the bleed valve 82 is opened; whereupon the pump catcher 54 may be safely removed to remove the pump 24. It will also be noted that when high pressure power fluid is being applied to the smaller tubing string

14, the pressure of this fluid is transmitted through the valve seat 126 (FIG. 6) to move the small ball valve 140 to the right against the valve seat 124. Thus, the pressure of the high pressure power fluid is then applied to the pressure gauge 52 to again advise the operator of the system of the highest pressure being applied to the pump installation.

From the foregoing, it will be apparent that the present invention provides a highly useful and simply operated control system for free pump installations. The only valve structure utilized in the system which is subjected to the abrasive well fluids comprises ball-type valves and ball valve seats which are historically the least subject to wear by abrasive fluids. Also, only two valve seats are used in the abrasive fluid environment to minimize the parts subject to wear. Further, these two valve seats are reversible for convenience in repair. The entire control system utilizes the maximum of standard and commercially available parts to provide an economical construction. The highest pressure being applied to the free pump installation is constantly indicated, regardless of whether the high pressure is being applied to the large string or the small string. It will also be apparent that the present control system may be installed on substantially any existing free pump installation, regardless of variations in the spacings between the large and small tubing strings.

Changes may be made in the combination and arrangement of parts or elements as heretofore set forth in the specification and shown in the drawings, it being understood that changes may be made without departing from the spirit and scope of the invention as defined in the following claims.

We claim:

1. A control system for a free pump installation, including a large tubing string and a small tubing string positioned in a well and connected at their lower ends, a pump in the large tubing string, and a source of high pressure power fluid for operating the pump, comprising: a valve body having a first passage therethrough and an outlet passage intersecting the central portion of the first passage; means forming an outwardly facing valve seat in the first passage at each side of the outlet passage; means connecting the large tubing string to the first passage between one valve seat and the adjacent end of the first passage; means connecting the smaller tubing string to the first passage between the other valve seat and the adjacent end of the first passage; hand-operated valve means connecting the source of high pressure fluid to the opposite ends of the first passage for feeding the high pressure fluid into either end of the first passage; and a shuttle valve in the first passage responsive to pressures on the opposite ends thereof for alternately seating on the valve seats to simultaneously provide communication between the large tubing string and the outlet passage and between one end of the first passage and the smaller tubing string for removing the pump through the large tubing string, and, alternately, simultaneously provide communication between the small tubing string and the outlet passage and between the other end of the first passage and the larger tubing string for inserting the pump in the well through the large tubing string.
2. A system as defined in claim 1 wherein said shuttle valve comprises a pair of ball valves on opposite sides of the valve seats, and a spacer extending through the valve seats retaining the ball valves a distance apart greater than the distance between the valve seats, whereby one valve seat is always open for the flow of the fluid into the outlet passage.
3. A system as defined in claim 2 wherein said spacer comprises a sleeve having openings in the walls thereof

for flow between either one of said tubing strings and the outlet passage.

4. A system as defined in claim 3 wherein said sleeve is separate from the ball valves.

5. A system as defined in claim 2 characterized further to include a slotted liner in said first passage on the outer side of each valve seat receiving the respective ball valve, each liner having a variable inner diameter to restrict the flow of fluid around the respective ball valve when the other ball valve is on its seat, whereby both ball valves will be unseated when equal pressures are applied to the opposite ends of said first passage.

6. A system as defined in claim 2 wherein said valve seats are removable and characterized further to include a slotted liner in the first passageway on the outer side of each valve seat to support the respective ball valve and providing communication between the first passageway and the respective tubing string, each of said liners having a decreased inner diameter near the outer end thereof.

7. In a free pump system, including a large tubing string and a small tubing string positioned in a well and connected at their lower ends, a pump in the large tubing string, and a source of high pressure power fluid for operating the pump, the improvement comprising:

a valve body connected to both the large and small tubing strings and having a pair of power fluid inlets, said body also having an outlet port;

means connecting the source of high pressure power fluid to both of said inlets for alternately feeding high pressure power fluid to said inlets;

means in the valve body for connecting one inlet to the smaller tubing and the large tubing to the exhaust port while power fluid is being fed to said one inlet and, alternately, connecting the other inlet to the larger tubing string and connecting the smaller tubing string to the exhaust port while high pressure power fluid is being fed to said other inlet;

a pressure-measuring bore in the valve body having a first end and a second end;

means connecting the first end of the pressure bore to the smaller tubing string;

means connecting the second end of the pressure bore to the larger tubing string;

a pressure gauge;

means connecting the central portion of the pressure bore to the pressure gauge; and

means in the pressure bore providing communication only between the central portion of the pressure bore and the end of the pressure bore having the highest pressure.

8. A system as defined in claim 7 wherein said second valve means comprises a valve seat in the pressure bore on each side of said central portion of the pressure bore, a slotted liner between said valve seats, and a ball valve loosely disposed in said liner, said ball valve being of a size to seat on either of said valve seats.

9. A control system for a free pump installation, including a large tubing string and a small tubing string positioned in a well and connected at their lower ends, a pump in the large tubing string, and a source of high pressure power fluid for operating the pump, comprising:

a valve body having a first passage therethrough and an outlet passage intersecting the central portion of the first passage;

means forming an outwardly facing valve seat in the first passage at each side of the outlet passage;

means connecting the larger tubing string to the first passage between one valve seat and the adjacent end of the first passage;

means connecting the smaller tubing string to the first passage between the other valve seat and the adjacent end of the first passage;

hand-operated valves connecting the source of high pressure fluid to the opposite ends of the first passage for feeding the high pressure fluid into either end of the first passage;

a shuttle valve in the first passage responsive to differential pressures on the opposite ends thereof for controlling the flow of fluid to and from the large and small tubing strings;

a pressure-measuring bore in the valve body having a first end and a second end;

means connecting the first end of the pressure bore to the smaller tubing string;

means connecting the second end of the pressure bore to the larger tubing string;

a pressure gauge;

means connecting the central portion of the pressure bore to the pressure gauge; and

means in the pressure bore providing communication only between the central portion of the pressure bore and the end of the pressure bore having the highest pressure.

10. A system as defined in claim 9 wherein said second valve means comprises a valve seat in the pressure bore on each side of the connection of the pressure bore to the pressure gauge, a slotted liner between said valve seats, and a ball valve slidably disposed in said liner, said ball valve being of a size to seat on either of said valve seats.

11. A control system for a free pump installation, including a large tubing string and a smaller tubing string positioned in a well and connected at the lower ends, a pump in the large tubing string, and a source of high pressure power fluid for operating the pump, comprising:

a valve body connected to the larger tubing, the smaller tubing and the source of high pressure power fluid;

means in the valve body controlling the flow of high pressure power fluid to the smaller tubing, and, alternately, the larger tubing for insertion, operation and removal of a pump from the larger tubing;

a pressure-measuring bore in the valve body having a first end and a second end;

means connecting the first end of the pressure bore to the smaller tubing;

means connecting the second end of the pressure bore to the larger tubing;

a pressure gauge;

means connecting the central portion of the pressure bore to the pressure gauge; and

means in the pressure bore providing communication only between the central portion of the pressure bore and the end of the pressure bore having the highest pressure.
